UNITED STATES PATENT OFFICE.

CHARLES S. BURTON, OF OAK PARK, ILLINOIS.

ACCENTUATING DEVICE FOR AUTOMATIC MUSICAL INSTRUMENTS.

No. 861,260

Specification of Letters Patent.

Patented July 30, 1907.

Application filed June 13, 1904. Serial No. 212,249.

To all whom it may concern:

Be it known that I, CHARLES S. BURTON, a citizen of the United States, residing at Oak Park, in the county of Cook and State of Illinois, have invented new and useful Improvements in Accentuating Devices for Automatic Musical Instruments, of which the following is a specification, reference being had to the accompanying drawings, forming a part thereof.

This invention is designed to provide, in an automatic musical instrument or player, new and improved means for accentuating automatically by means of the construction of the perforated sheet, any selected note or notes.

It consists of the features and characteristics of construction set out in the claims.

In the drawings:—Figure 1 is a fore-and-aft vertical section through the pneumatic action of an automatic player embodying my invention. Fig. 2 is a section at the line 2—2 on Fig. 1. Fig. 3 is a section at the line 20 3—3 on Fig. 1. Fig. 4 is a plan view of a portion of a perforated controlling sheet employed in my invention. Fig. 5 is a front elevation of the pneumatic action. Fig. 6 is a section at the line 6—6 on Fig. 5. Fig. 7 is a detail plan view of a portion of a perforated controlling sheet for use in my invention in a different form from that shown in Fig. 4. Fig. 8 is a detail top edge or plan view of a portion of a tracker board for use with the perforated sheet shown in Fig. 7, a portion of the top plate or mouth-piece being broken away to show the construction beneath. Fig. 9 is a section at the line 9—9 on Fig. 8. Fig. 10 is a similar section showing a slightly modified form of the mouth-piece or top plate of the tracker board. Fig. 11 is a detail inverted plan view of said mouth-piece in the form shown in Fig. 9. Fig. 35 12 is a perspective view of one of the elements or blocks making up the pneumatic action containing the ducts leading to the primary pneumatic. Fig. 13 is a perspective view of one of the spacing and partitioning plates. Fig. 14 is a section at the line 14—14 on Fig. 5.

40 A specific purpose of my invention is to avoid the necessity for a double set of air ducts or throats in the tracker-board in carrying out the principal purpose of providing means for causing the motor pneumatics to operate with two degrees of intensity at different times.

45 I have shown in the drawings a tracker-board, 1, of ordinary construction, that is, having a single set of air ducts, one duct 1^a being provided for each note to be struck or sounded by the player, and a perforated controlling sheet, 2, operated in the usual manner over the mouth of such tracker-board for controlling the ducts. I have shown the tracker-board, for convenience of illustrating the device with fewest details of mechanical construction, mounted by means of brackets, 3, upon the board, 4, of the pneumatic action. In the pneumatic action an exhaust or partial vacuum chamber, 5, extends over the entire range of the action containing

the primary pneumatics, 6, 6, 6, one for each key to be operated by the player. Another set of primary pneumatics, 7, 7, 7, etc., one for each key are arranged each in a separate chamber, 8, the chamber, 5, and the multiple chambers, 8, being bounded upon one side by the duct-board, 9, in which are ducts, 10, 10, 10, etc., connected with the ducts of the tracker-board respectively. The duct-board is made up of elements or duct blocks, 9, assembled with the spacing partitions, 9^a, between them, and end-blocks, 9^b, completing the structure and closing the chambers at the ends. Each of said ducts, 10, communicates with one of the pneumatics, 6, at a port, 10^a, and with the corresponding pneumatic, 7, through a port, 10^b. The primary pneumatics, 7, operate the valves, 11, 11, etc., for controlling the motor pneumatics, 12, 12, etc., in a manner well understood, that is, so that when the valve, 11, is seated over the port, 8^a, leading into the chamber, 8, the motor pneumatic is in communication through the port, 8^b, with the outer air, and is inflated; and when the position of the valve is reversed so that it closes the port, 8^b, the motor pneumatic is in communication through the port, 8^a, with the chamber, 8, and exposed to the exhaust tension therein, and is collapsed. Each of the pneumatics, 6, operates a valve, 14, controlling ports, 5^a, and 13^a, the former leading from the chamber, 5, and the latter from a chamber, 13, at the opposite side of the duct-board, 4, from the chamber, 5. Each of the valve chambers, 15, in which the valve, 14, is contained, 70 communicates by passage, 16, with the corresponding chamber, 8. The chamber, 5, is in communication, through any convenient means, as a pipe, 18, with a "low-tension" exhaust bellows or receiver (not shown), and the chamber, 13, is in communication, as by pipe, 90 18, with what may be termed a "high-tension" exhaust bellows or receiver not shown; the terms, "high", and "low", as applied to these chambers being relative merely, indicating simply that in the chamber, 5, there is maintained a lower degree of exhaust tension than in the chamber, 13. The primary pneumatics, 7, are each provided with a leak port, 19, but the primary pneumatics, 6, are without any leak port.

75 The perforated controlling sheet, 2, has the controlling apertures, 20, for registration with the duct mouths 100 in the tracker range in the usual parallel rows, and of such width as to afford free and instantaneous vent when they register with the tracker-range mouths respectively; and in addition to these apertures, 20, for certain purposes about to be explained, it has minute 105 perforations, 21, just in advance of certain of the apertures, 20. The perforations, 21, are substantially equal to the leak ports, 19, in the pneumatics, 7, so that the amount of air which is conducted to the tracker-range ducts when these minute apertures, 21, register 110 with the mouths of the ducts, is substantially equal to that which can pass through the leak port of the

corresponding primary pneumatic, 7. As the controlling sheet advances over the tracker-range it will happen, therefore, that when a minute perforation, 21, which, for convenience of mention, I term a "pilot port", passes the tracker board the corresponding primary pneumatic, 7, will not be affected, because its leak port will take care of all the air that can enter through the pilot port, 21. The primary pneumatic, 6, however, being without a leak port, will be affected by the air admitted through the pilot port, 21, and will be inflated, causing the valve, 14, to shift from the position shown in Fig. 1, so that it will uncover the port, 5^a, and cover the port, 13^a, thereby putting the corresponding chamber, 8, in communication with the low-tension chamber, 5, instead of with the high-tension chamber, 13. Immediately after this has occurred, the full width of the aperture, 20, of the perforated sheet reaching the mouth of the tracker duct admits air freely to the primary pneumatic, 7, far in excess of the capacity of its leak port, 19, and the inflation of such primary pneumatic which results operates the valve, 11, to cause the motor pneumatic, 12, to be collapsed and to operate the proper key of the instrument. The force with which the motor pneumatic strikes the blow will be that afforded by the low-tension from the chamber, 5, since it is in communication with that chamber when the valve, 11, is opened by the primary pneumatic, 7. When an aperture, 20, which is not preceded by the pilot port, 21, reaches the mouth of the tracker-duct, the primary pneumatic, 7, will be inflated instantly and before the primary pneumatic, 6, because the pneumatic, 6, is exposed to the low exhaust tension in its chamber, whereas the pneumatic, 7, is exposed to the high tension derived from the chamber, 13; and by such instantaneous action of the primary pneumatic, 7, before the valve, 14, is shifted, the motor pneumatic, 12, is collapsed by the high exhaust tension and strikes a harder blow than if it had been collapsed by the low-tension derived from the chamber, 5. The result is that all notes sounded by means of an aperture, 20, which are not preceded by a perforation, 21, will be sounded loud, and those which are produced by the apertures preceded by the pilot perforation will be sounded softly. The arranger of the perforated sheet can therefore determine the accented notes, either for the purpose of marking the accented beats of the measures throughout the entire chord, or for distinguishing the melody from the accompaniment, or vice versa, or for any other purpose for which, according to his musical taste and judgment, such selected accentuation is desirable.

It will be seen that if an entire group of the ducts, 10, is cut off or closed between the ports, 10^a and 10^b, leaving only the latter ports in communication with the tracker-ducts, all notes in such group will be sounded with the force derived from the high-tension chamber. It is possible, therefore, independently of the pilot perforations, to accentuate all the notes in any group whose ducts, 10, are provided with closures. The entire range of the instrument may be divided into as many groups as desirable for the purpose of such accentuation by groups or as a whole. The drawings therefore illustrate a construction in which the ducts, 10, are controlled in two groups, one for the lower part or bass and the other for the upper part or treble of the

instrument. For this purpose, the duct-board has at the forward side the recess, 9^c, in which there are seated the two slides, 9^d and 9^e, which are in the nature of valves having in them the portions, 10^c, of the ducts, 10, said portions terminating at the inner surface of said slides or valves, having their opposite terminal openings spaced from each other suitably to cause them to register simultaneously with the outer ends of the respective ports 10^a and 10^b, of the ducts, 10. The recess, 9^c, is sufficiently wider than the valves 75 or slides, 9^d and 9^e, to permit the latter a range of movement both up and down from the position at which the terminal mouths of their ducts register as described with the ports, 10^a and 10^b. In addition to said portions, 10^c, of the air ducts, the valve boards or 80 slides have ducts, 10^f, in the same vertical fore-and-aft planes with the ducts, 10^c, respectively, said apertures extending entirely through the valve boards and opening at both ends, that is, at the inner and outer surfaces of said boards, the inner end openings being just 85 below the lower terminal openings of the ducts, 10^c. These valve boards or slides being lodged in the recess, 9^c, are retained and held normally at the intermediate position in the width of the recess at which their duct terminals register with the ports, 10^a and 10^b, of the air 90 ducts by means of bow springs, 50, 50, mounted at their middle points on the forward side of the duct board and bearing at their ends upon the pins, 51, 51, 51, 51, near the ends and upper and lower edges of said slides (see Fig. 5). Guards, 52, fastened upon the front 95 surface of the duct board extend over the forward surface of the valve boards or slides and retain them with slight pressure seated in the recess, 9^c. When the slides or valve boards are at their intermediate—which may be termed their normal—position, at which the 100 springs, 50, 50, tend to hold them, the portions, 10^c, of the ducts communicate at the upper end with the remaining upper portion, and at the lower end with the remaining lower portion of the ducts, 10, and thereby effect communication from the tracker ducts with 105 both pneumatics, 6 and 7. If the valve boards or slides are depressed to the limit of their range of vertical movement in the recess, 9^c, the portions, 10^c, of the ducts in said valve boards are closed at both ends, and the primary pneumatics, 6, are cut off from the 110 tracker ducts while the primary pneumatics, 7, remain in communication therewith. With this adjustment it will be seen that the pneumatics, 7, will be in communication only with the high tension chamber and that all the notes sounded while this adjustment continues 115 will be sounded loudly or with stroke corresponding to said high tension. If the valve boards or slides are lifted to the upper limit of their range of adjustment, the ducts, 10^c, will be closed at their upper end, and communication from the tracker ducts to the pneumatics, 6, will be thereby cut off and at the same time the ducts, 10^f, will be brought into registration at their inner ends with the outer ends of the ports, 10^a, leading to the pneumatics, 6, and thereby said pneumatics will be put in communication with the outer 120 air and will be inflated, causing them to seat the valves, 14, which they control, in position for admitting the air from the low tension chamber into the chambers of all the primary pneumatics, 7, of the group which is included within the scope of the slide or valve board 130

which is thus adjusted. With this adjustment therefore of either valve board, the notes in the portion of the manual to which such valve board corresponds will be sounded softly by reason of the motor pneumatics which control the strikers for them being exposed to the low tension. For the purpose of operating the slides or valve boards, 9^a and 9^c, I provide rock shafts, 54 and 55, the former for the bass and the latter for the treble, journaled on the forward side 10 of the pneumatic action above the recess, 9^c, and having lever arms, 54^a, 54^b, and 55^a, 55^b, respectively, which engage the operating stems, 56, of the valve boards or slides, 9^a and 9^c, as seen in Fig. 5. These shafts have each the additional lever arms, 57 and 58, 15 the former projecting upward and the latter downward, and engaging the elongated eyes, 59, 59, mounted respectively upon the vibrating leaves of two horizontally hinged pneumatics, 60 and 61, which are oppositely mounted upon the forward side of the action and are 20 controlled by primary pneumatics, 62 and 63, respectively, said primary pneumatics for the bass being located at the left-hand end and for the treble at the right-hand end of the group or row of pneumatics, 7, in chambers, 84, partitioned from the adjacent chambers 25 for the pneumatics, 7, respectively, but in direct communication by means of ducts, 65, with the high tension chamber, and having their valves, 63^a, operating in the same manner as the valves, 11, to control communication of the pneumatics, 60 and 61, with said 30 high tension chamber or with the outer air according to the condition of said primary pneumatics as inflated or collapsed. The primary pneumatics, 62 and 63, are connected by ducts, 66, with vent ports controlled by valves, 67, held normally seated by springs, 68, and 35 provided each with a push button, 69, accessible to the operator for opening said valves at will and thereby venting the primary pneumatics and bringing the pneumatics, 60 and 61, into action. If the pneumatic, 60, which is connected with the downwardly extending 40 lever arm, 58, of the rock shaft, 55, is brought into action by depressing the corresponding button, 69, the valve board or slide will be depressed and the primary pneumatic, 6, of the treble group being thereby all cut off from communication with the tracker board, 45 will remain collapsed, and all the tones in the treble range sounded during this adjustment will be produced by strokes caused by the high tension chamber and will be correspondingly loud. If the other treble push button is depressed and the pneumatic which is connected 50 with the upwardly-extending arm, 57, of the rock shaft, 55, is brought into action, the valve board or slide will be lifted and thereby the primary pneumatic, 6, being cut off from communication with the tracker board but opened to the outer air, will become 55 and remain inflated, causing all the tones in the treble range sounded during this adjustment to be produced by strokes caused by the low tension chamber and to be correspondingly soft. Similar control of the bass tones will be obtained by the other two push buttons, 60 causing the bass pneumatics, 60 and 61, to rock one way or the other the shaft, 54. The ducts, 66, may have branches, 66^a, leading to ducts in the tracker board, which may be vented by correspondingly situated apertures, 75, 75, in the controlling sheet to produce 65 automatically the same results which are pro-

duced by the operator using the buttons, 69. This modification is obvious and requires no further explanation.

I do not limit myself to the particular arrangement of the two groups of pneumatics, 6 and 7, nor to the particular mechanism shown for cutting off the group of pneumatics, 6, from the tracker board ducts, and opening them to the outer air for controlling the tone of the entire instrument or portion thereof corresponding to the valve boards, 9^a and 9^c, respectively, and anyone familiar with the art will readily be able to devise other arrangements and relative locations of the several parts to produce the same result by means of the same principle.

It will be obvious that the pilot perforation, 21, when placed directly in advance of the full sized aperture, 20, prevents making the bridge or interval between two consecutive full sized apertures which would be cut for repeating the same note, so short as it could otherwise be made, and thus may tend to prevent the rapid repetition of a note with the low-tension or light stroke. This difficulty obviously could be overcome by giving the paper a more rapid travel than it would receive if the pilot perforations were not being employed; but to avoid the necessity of resorting to this means, the expedient shown in Figs. 8, 9 and 10 with respect to the construction of the tracker-range, and in Fig. 7 with respect to the perforated roll, may be employed. This expedient consists in providing the tracker-range with a metal face-plate, 70, in which there are apertures, 71, forming the ordinary mouth of the tracker-ducts 1^a, which are made shorter than the width of the ducts themselves in the tracker-board, and register with said ducts 1^a at one edge, and in which there are additional fine perforations, 72, which open at the outer surface of the plate, 70, a little back of the transverse line of apertures, 71, at the inner face in position to register with the portion of the tracker-duct 1^a not covered by the aperture, 71. This may be accomplished by drilling the apertures, 72, obliquely through the plate, as shown in Fig. 10, or by cutting upon the under side of the plate or upon the upper side of the tracker-board which is to be faced by the plate, a short channel, 73, leading from the inner end of the perforation, 72, transversely with respect to the tracker-board to the duct, 1^a as illustrated in Figs. 9 and 11, the purpose in either case being to afford a passage from the opening of the perforation, 72, through the upper surface of the face plate into the duct 1^a in the tracker-board, thus giving to said duct two mouths, the lesser of which shall be reached by any given transverse line of the paper in its travel sooner than the other. The perforated roll will then have the apertures, 20, as usual, but not wider than the aperture, 72, and the pilot perforation, 21, instead of standing directly in advance of the aperture, 20, will stand at the side of said aperture even with the forward end of it. The provision of the perforation, 72, in the mouth of the tracker-board set back of the main mouth, 71, causes the pilot perforation, 21, which is only even with the forward end of the main perforation, 20, to afford vent to the primary pneumatic, 6, in advance of the vent which the primary pneumatic, 7, receives, by as much as the aperture, 71, is back of the aperture, 72,

thus effecting the same result as the location of the pilot aperture in front of the main aperture when the tracker duct 1^a has only one mouth.

I claim:—

5. 1. An automatic musical instrument or player, comprising, in combination with pneumatically operated playing devices, two sets of primary pneumatics, one set adapted to be operated by less air supply than the other; a set of tracker ducts, each of which is connected with a primary of each set; means for controlling admission of air to the ducts adapted to admit, first, a less and afterward a greater supply; two sources of air under tension for actuating the playing devices and valves which intervene between said sources and the playing devices operatively connected with the primary pneumatics which require the less air supply.

2. An automatic musical instrument or player, comprising, in combination with pneumatically operated playing devices, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the playing devices; two sets of valves successively intervening between said sources on one hand and the pneumatic playing devices on the other, the set which directly controls said sources being operatively connected with the primary pneumatics which require the less air supply, and the other set being operatively connected with the primary pneumatics requiring the greater air supply.

3. An automatic musical instrument or player, comprising, in combination with playing devices and motor pneumatics which operate them, two sets of primary pneumatics, one set adapted to be operated by less air supply than the other; a set of tracker ducts, each of which is connected with a pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other hand, the first set in order from said sources being operatively connected with the primary pneumatics which require the less air supply, and the first set in order from the motor pneumatics being operatively connected with the primary pneumatics requiring the greater air supply.

4. An automatic musical instrument or player, comprising, in combination with motor pneumatics, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other, the set next in order from said sources being operatively connected with the primary pneumatics which require the less air supply, the other set being operatively connected with the primary pneumatics requiring the greater air supply, and means for cutting off communication through the tracker ducts from the first set of primary pneumatics to the second.

5. An automatic musical instrument or player, comprising, in combination with motor pneumatics, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other, the set next in order from said sources being operatively connected with the primary pneumatics which require the less air supply, the other set being operatively connected with the primary pneumatics requiring the greater air supply, and means for cutting off communication through the tracker ducts from the first set of primary pneumatics to the second.

6. An automatic musical instrument or player, comprising, in combination with motor pneumatics, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other, the set next in order from said sources being operatively connected with the primary pneumatics which require the less air supply, the other set being operatively connected with the primary pneumatics requiring the greater air supply, and means for cutting off communication through the tracker ducts from the first set of primary pneumatics to the second.

7. An automatic musical instrument or player, comprising, in combination with motor pneumatics, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other, the set next in order from said sources being operatively connected with the primary pneumatics which require the less air supply, the other set being operatively connected with the primary pneumatics requiring the greater air supply, and pneumatically operated means for cutting off communication through the tracker ducts from the first to the second set of primary pneumatics to the second.

8. An automatic musical instrument or player, comprising, in combination with motor pneumatics, two sets of primary pneumatics, one set adapted to be operated by less air supply than the other; a set of tracker ducts, each of which is connected with a primary pneumatic of each set; means for controlling the admission of air to the ducts, adapted to admit first a less and afterward a greater supply; two sources of air under tension for actuating the motor pneumatics; two sets of valves successively intervening between said sources on the one hand and the motor pneumatics on the other, the set next in order from said sources being operatively connected with the primary pneumatics which require the less air supply, and the other set being operatively connected with the primary pneumatics requiring the greater air supply, and pneumatically operated means for cutting off communication through the tracker ducts from the first to the second set of primary pneumatics, and for opening communication of the second set with the outer air.

9. In an automatically operated musical instrument, in combination, two sets of primary pneumatics, a tracker board and a set of air ducts each of which communicates with a primary pneumatic of each set, and with the tracker board said primary pneumatics of the two sets being adapted to be operated respectively by a less and a greater supply of air; a controlling sheet having larger and smaller apertures for communication with the same ducts respectively, the smaller aperture being located with respect to the corresponding portion of the entrance to the duct in position to arrive at said portion of the entrance in advance of the arrival of the larger aperture at the corresponding portion of the entrance to said duct.

10. An automatic musical instrument or player, comprising two sets of primary pneumatics, those of one set having leak ports and those of the other set being without leak ports; a tracker board having a set of ducts, each of which leads to one primary of each set; means for admitting air through the tracker ducts in quantity not greater than the capacity of the leak ports and subsequently admitting a greater quantity; two sources of air under tension; a general air chamber containing all the pneumatics without leak ports and being in communication with one of said sources; individual chambers containing the pneumatics of the other set and ducts connecting said individual chambers with the other chamber; a second general air chamber communicating with the other source of air.

and having ports for communication with the first-mentioned general air chamber corresponding respectively to the primaries in the latter, and valves operated by said primaries for controlling such communication.

5 11. An automatic musical instrument or player, comprising in combination with playing devices and motor pneumatics for operating them, a set of primary pneumatics which control such motor pneumatics respectively; individual chambers in which said primaries are located; a second set of primary pneumatics corresponding respectively to those of the first-mentioned set; a general air chamber in which all said second set of primary pneumatics are located; a second general air chamber and two sources of air under tension communicating with said 15 general air chambers; ducts from said individual air chambers communicating with both the general air chambers; valves which control the ports of communication of said ducts with said general air chambers; primary pneumatics in the first general air chamber connected with 20 and operating said valves; a tracker board having a set of ducts each of which communicates with a primary pneumatic of each set, said primary pneumatics of the two sets differing in respect to the freedom of vent or leakage, and means for admitting air to the tracker ducts to an extent 25 not materially greater than the leakage of the primary pneumatics having the greater leakage and for subsequently admitting air to a greater extent.

12. An automatic musical instrument or player, comprising, in combination with playing devices and motor pneumatics for operating them, a set of primary pneumatics for controlling said motor pneumatics respectively; two general air chambers connected respectively with two sources of air under tension; individual chambers in which the primary pneumatics of the first set are inclosed; a 35 duct from each of said individual chambers having a port of communication with each of the two general air chambers; a valve for each of said ducts oscillating for closing their said ports alternatively; primary pneumatics in one of said chambers operatively connected with said valves 40 respectively; a tracker board having a set of ducts, each of which communicates with one primary pneumatic of each set; means controlling the admission of air into said tracker ducts adapted to admit a lesser and a greater quantity; the primary pneumatics of the first-mentioned 45 set being adapted to be operated only by the greater quantity, and the other primary pneumatics being adapted to be actuated by either the lesser or the greater quantity.

13. An automatic musical instrument or player, comprising in combination with playing devices and motor pneumatics for actuating them respectively; a set of primary pneumatics for controlling the motor pneumatics; individual chambers for each of said primary pneumatics; two general air chambers and ducts from the individual chambers respectively, each having a port of communication with each of said general air chambers; primary pneumatics in one of said chambers controlling communication of said ducts through said ports with said general chambers respectively, said primary pneumatics being adapted to be operated by a less supply of air than the primaries of the first-mentioned set; a tracker board having a 50 set of ducts each of which communicates with a primary of each set; means for controlling the entrance of air through said ducts adapted to admit successively a lesser and a greater quantity, and means for cutting off communication of said ducts with the primaries of the second set.

65 14. An automatic musical instrument or player, comprising in combination with playing devices and motor pneumatics for actuating them respectively; a set of pri-

mary pneumatics for controlling the motor pneumatics; individual chambers for said primary pneumatics respectively; two general air chambers and ducts from the individual chambers respectively, each having a port of communication with each of said general air chambers; primary pneumatics in one of said chambers controlling communication of said ducts through said ports with said general chambers respectively, said primary pneumatics being adapted to be operated by a less supply of air than the primaries of the first-mentioned set; a tracker board having a set of ducts, each of which communicates with a primary of each set; means for controlling the entrance of air through said ducts, adapted to admit successively a lesser and a greater quantity, and means for cutting off communication of said ducts with the primaries of the second set, and for simultaneously giving said primaries communication with the outer air.

70 15. An automatic musical instrument or player, comprising, in combination with playing devices and motor pneumatics for actuating them respectively, a set of primary pneumatics for controlling such motor pneumatics; individual air chambers for said primary pneumatics respectively; two general air chambers in communication with two sources of air under tension; ducts from said individual air chambers having each a port of communication with each of the two general air chambers; primary pneumatics in one of said chambers for controlling said ports; a tracker board having a set of ducts, each of which communicates with a primary of each set; a valve board containing a portion of each of said ducts intermediate between the two sets of primaries, movable to effect and defeat air communication from the tracker board to the second set of primaries; means for holding such valve board normally in position for effecting such communication; a motor pneumatic for moving it from that position; a primary pneumatic for controlling such motor pneumatic and means for venting the primary pneumatic.

75 16. An automatic musical instrument or player, comprising, in combination with playing devices and motor pneumatics for actuating them respectively, a set of primary pneumatics for controlling such motor pneumatics; individual air chambers for said primary pneumatics respectively; two general air chambers in communication with two sources of air under tension; ducts from said individual air chambers having each a port of communication with each of the two general air chambers; primary pneumatics in one of said chambers for controlling said ports; a tracker board having a set of ducts, each of which communicates with a primary of each set; a valve board containing a portion of each of said ducts which extends intermediate between the two primaries; means for holding said valve board normally in position for registering its ducts with the remaining portions thereof and effecting communication therethrough to both primaries, said board being movable in two directions away from said normal position for interrupting such communication by either movement and having a set of ports open at one end to the outer air and adapted at the other end for registering with the ducts leading to the primaries of the second set at one of said positions.

110 In testimony whereof, I have hereunto set my hand in the presence of two witnesses, at Chicago, Illinois, this 6th day of June, A. D., 1904.

CHAS. S. BURTON.

In the presence of—
FREDK. G. FISCHER,
J. S. ABBOTT.
